(57) **CLAIM**

The ornamental design for a drive shaft, as shown and described.

DESCRIPTION

FIG. 1 is a front, top perspective view of a drive shaft, showing my new design;

FIG. 2 is a front, bottom perspective view thereof;

FIG. 3 is a rear, top perspective view thereof;

FIG. 4 is a rear, bottom perspective view thereof;

FIG. 5 is a top view thereof;

FIG. 6 is a bottom view thereof;

FIG. 7 is a rear view thereof;

FIG. 8 is a front view thereof; and,

FIG. 9 is a rear, top perspective view thereof, shown in a condition of use.

The broken lines in the drawings illustrate portions of the drive shaft that form no part of the claimed design. The broken lines depicting an engine in FIG. 9 show environmental structure which forms no part of the claimed design.
